(57) **ABSTRACT**

A multilayer coil component includes an element body, a coil, and a terminal electrode. The element body includes a first main face, second main face, first end face, second end face, first side face and second side face. The terminal electrode is connected to the coil. The terminal electrode includes a main-face electrode portion provided on the first main face. The coil includes a plurality of coil conductors. The plurality of coil conductors includes a first coil conductor disposed closest to the first main face to oppose to the main-face electrode portion and a second coil conductor disposed closer to the second main face than the first coil conductor. The first coil conductor has a width narrower than a width of the second coil conductor. The first coil conductor has an aspect ratio higher than an aspect ratio of the second coil conductor.

TECHNICAL FIELD

The present disclosure relates to a multilayer coil component.

BACKGROUND

Japanese Unexamined Patent Publication No. 2014-22426 discloses a multilayer inductor including a laminate formed by laminating a plurality of magnetic material layers, a coil disposed in the laminate, and an external electrode provided on the lower face of the laminate. In this multilayer inductor, the coil and the external electrode are disposed to be opposed to each other.

SUMMARY

In the multilayer inductor, stray capacitance (parasitic capacitance) is formed between the coil and the external electrode. This deteriorates the characteristics of the multilayer inductor.

One aspect of the present disclosure provides a multilayer coil component capable of preventing deterioration in characteristics.

A multilayer coil component according to one aspect of the present disclosure includes an element body, a coil, and a terminal electrode. The element body has a rectangular parallelepiped shape. The element body includes a first main face and a second main face opposed to each other in a first direction, a first end face and a second end face opposed to each other in a second direction intersecting the first direction, and a first side face and a second side face opposed to each other in a third direction intersecting the first direction and the second direction. The coil includes a coil axis along the first direction and is disposed in the element body. The terminal electrode is electrically connected to the coil. The terminal electrode includes a main-face electrode portion provided on the first main face. The coil includes a plurality of coil conductors disposed to be separated from each other in the first direction and electrically connected to each other. The plurality of coil conductors includes a first coil conductor disposed closest to the first main face to oppose to the main-face electrode portion and a second coil conductor disposed closer to the second main face than the first coil conductor. The first coil conductor has a width narrower than a width of the second coil conductor. The first coil conductor has an aspect ratio higher than an aspect ratio of the second coil conductor.

In this multilayer coil component, the first coil conductor is disposed closest to the first main face among the plurality of coil conductors and is opposed to the main-face electrode portion. Thus, stray capacitance is formed between the first coil conductor and the main-face electrode portion depending on the area where the first coil conductor is opposed to the main-face electrode portion. The width of the first coil conductor is narrower than the width of the second coil conductor disposed closer to the second main face than the first coil conductor. Thus, the area where the first coil conductor is opposed to the main-face electrode portion is smaller than that when the width of the first coil conductor is about equal to the width of the second coil conductor. As a result, it is possible to reduce the stray capacitance formed between the first coil conductor and the main-face electrode portion. Accordingly, it is possible to prevent the self-resonant frequency (SRF) of the multilayer coil component

from lowering. The first coil conductor has an aspect ratio higher than an aspect ratio of the second coil conductor. Thus, it is possible to increase the cross-sectional area of the first coil conductor as compared with the aspect ratio of the first coil conductor being about equal to the aspect ratio of the second coil conductor. Accordingly, it is possible to prevent the Q value of the multilayer coil component from decreasing. From the above, it is possible to prevent deterioration in the characteristics of the multilayer coil component.

The cross-sectional area of the first coil conductor may be equal to the cross-sectional area of the second coil conductor. In this case, it is possible to reliably prevent the Q value from decreasing.

The plurality of coil conductors may have a width becoming narrower toward the first main face and an aspect ratio becoming higher toward the first main face. Thus, it is possible to further prevent the deterioration in the characteristics of the multilayer coil component.

The first coil conductor may have, when viewed from the first direction, an outer edge aligning with an outer edge of the second coil conductor. In this case, the inner diameter of the first coil conductor is increased, and it is possible to improve the Q value and the inductance (L).

The terminal electrode may further include an end-face electrode portion provided on the first end face. The first coil conductor may be opposed to the end-face electrode portion. The first coil conductor may have, when viewed from the first direction, an inner edge aligning with an inner edge of the second coil conductor. In this case, the distance between the first coil conductor and the end-face electrode portion is widened, and it is possible to reduce the stray capacitance formed between the first coil conductor and the end-face electrode portion. Accordingly, it is possible to further prevent the self-resonant frequency of the multilayer coil component from lowering.

The coil may include a pair of first coil regions opposed to each other sandwiching the coil axis in the second direction and a pair of second coil regions opposed to each other sandwiching the coil axis in the third direction. When viewed from the first direction, the inner edge of the first coil conductor may align with the inner edge of the second coil conductor in the pair of first coil regions, and an outer edge of the first coil conductor may align with an outer edge of the second coil conductor in the pair of second coil regions. In this case, the distance between the first coil conductor and the end-face electrode portion is widened in the second coil region, and it is possible to reduce the stray capacitance formed between the first coil conductor and the end-face electrode portion. Accordingly, it is possible to prevent the self-resonant frequency of the multilayer coil component from lowering. In addition, the inner diameter of the first coil conductor is increased in the second coil region, and it is possible to improve the Q value and the inductance (L). From the above, it is possible to improve the Q value and the inductance (L) while further preventing the self-resonant frequency of the multilayer coil component from lowering.

BRIEF DESCRIPTION OF THE DRAWINGS

FIG. 1 is a perspective view of a multilayer coil component according to a first embodiment;

FIG. 2 is a top view of the multilayer coil component in FIG. 1;

FIG. 3 is a side view of the multilayer coil component in FIG. 1;

FIG. 4 is a cross-sectional view taken along the line IV-IV in FIG. 1;

FIG. 5 is a cross-sectional view taken along the line V-V in FIG. 1;

FIG. 6 is a perspective view of a multilayer coil component according to a second embodiment;

FIG. 7 is a top view of the multilayer coil component in FIG. 6;

FIG. 8 is a side view of the multilayer coil component in FIG. 6;

FIG. 9 is a cross-sectional view taken along the line IX-IX in FIG. 6;

FIG. 10 is a cross-sectional view taken along the line X-X in FIG. 6; and

FIG. 11 is another cross-sectional view taken along the line IV-IV in FIG. 1.

2f extend in the second direction D2 in such a way as to connect the end faces 2a and 2b. The side faces 2e and 2f also extend in the first direction D1 in such a way as to connect the main faces 2c and 2d. The multilayer coil component 1 is, for example, solder-mounted on an electronic device. The electronic device is, for example, a circuit board or an electronic component. In the multilayer coil component 1, the main face 2c constitutes a mounting surface opposed to the electronic device.

10 The element body 2 is formed by laminating a plurality of insulator layers (not shown) in the first direction D1. The element body 2 includes a plurality of insulator layers laminated in the first direction D1. In the element body 2, the lamination direction in which the insulator layers are laminated is aligned with the first direction D1. In the actual element body 2, the insulator layers are integrated in such a way that boundaries between the insulator layers cannot be visually recognized.

15 Each insulator layer is formed of a dielectric material containing a glass component. That is, the element body 2 contains, as a compound of the elements constituting the element body 2, a dielectric material containing a glass component. The glass component is, for example, borosilicate glass. The dielectric material is, for example, BaTiO₃-based, Ba(Ti, Zr)O₃-based, or (Ba, Ca)TiO₃-based dielectric ceramic. Each insulator layer is formed by a sintered body of a ceramic green sheet containing a glass-ceramic material.

20 The terminal electrodes 3 and 4 are electrically connected to the coil 10. The terminal electrodes 3 and 4 are disposed at the respective end portions of the element body 2 in the second direction D2. The terminal electrodes 3 and 4 are separated from each other in the second direction D2. The terminal electrodes 3 and 4 are embedded in the element body 2. The terminal electrodes 3 and 4 are disposed in two recesses provided at the respective end portions of the element body 2 in the second direction D2. The two recesses are formed in shapes corresponding to the terminal electrodes 3 and 4. The terminal electrodes 3 and 4 are in contact with the inner surfaces of the respective recesses. The terminal electrodes 3 and 4 have, for example, the same shape.

25 The terminal electrode 3 is provided on the end face 2a side of the element body 2. The terminal electrode 3 is provided from the end face 2a to the main face 2c. The terminal electrode 3 is disposed in the recess provided from the end face 2a to the main face 2c of the element body 2. In the present embodiment, the surface of the terminal electrode 3 is substantially flush with the end face 2a and the main face 2c.

30 The terminal electrode 3 has an L shape when viewed from the third direction D3. The terminal electrode 3 includes an electrode portion 3a and an electrode portion 3b. The electrode portion 3a and the electrode portion 3b are connected at the ridge portion (the corner portion formed by the main face 2c and the end face 2a) of the element body 2, and are electrically connected to each other. In the present embodiment, the electrode portion 3a and the electrode portion 3b are integrally provided and are continuous with each other. The electrode portion 3a is provided on the end face 2a and extends along the first direction D1. The electrode portion 3a has a rectangular shape when viewed from the second direction D2. The electrode portion 3b is provided on the main face 2c and extends along the second direction D2. The electrode portion 3b has a rectangular shape when viewed from the first direction D1.

35 The terminal electrode 4 is provided on the end face 2b side of the element body 2. The terminal electrode 4 is

DETAILED DESCRIPTION

Hereinafter, embodiments of the present invention will be described in detail with reference to the accompanying drawings. In the description of the drawings, identical or equivalent elements are denoted by the same reference signs, and overlapped descriptions are omitted.

First Embodiment

With reference to FIGS. 1 to 5, a multilayer coil component 1 according to a first embodiment will be described. The multilayer coil component 1 includes an element body 2 having a rectangular parallelepiped shape, terminal electrodes 3 and 4 disposed at respective end portions of the element body 2, a coil 10, and connecting conductors 23 and 24. The rectangular parallelepiped shape includes a rectangular parallelepiped shape in which the corner portions and the ridge portions are chamfered, and a rectangular parallelepiped shape in which the corner portions and the ridge portions are rounded. In FIGS. 1 to 3, the element body 2 is shown by a broken line.

The element body 2 has end faces 2a and 2b opposed to each other, main faces 2c and 2d opposed to each other, and side faces 2e and 2f opposed to each other. In the following description, it is assumed that the direction in which the main faces 2c and 2d are opposed to each other is a first direction D1, that the direction in which the end faces 2a and 2b are opposed to each other is a second direction D2, and that the direction in which the side faces 2e and 2f are opposed to each other is a third direction D3. The first direction D1, the second direction D2, and the third direction D3 intersect each other. The first direction D1, the second direction D2, and the third direction D3 are orthogonal to each other in this embodiment. In the present embodiment, the first direction D1 is the height direction of the element body 2. The second direction D2 is the length direction of the element body 2. The second direction D2 is also the long-sides direction of the main faces 2c and 2d. The third direction D3 is the width direction of the element body 2. The third direction D3 is also the short-sides direction of the main faces 2c and 2d.

The end faces 2a and 2b extend in the first direction D1 in such a way as to connect the main faces 2c and 2d. The end faces 2a and 2b also extend in the third direction D3 in such a way as to connect the side faces 2e and 2f. The main faces 2c and 2d extend in the second direction D2 in such a way as to connect the end faces 2a and 2b. The main faces 2c and 2d also extend in the third direction D3 in such a way as to connect the side faces 2e and 2f. The side faces 2e and

disposed from the end face $2b$ to the main face $2c$. The terminal electrode 4 is disposed in the recess provided from the end face $2b$ to the main face $2c$ of the element body 2 . In the present embodiment, the surface of the terminal electrode 4 is substantially flush with the end face $2b$ and the main face $2c$.

The terminal electrode 4 has an L shape when viewed from the third direction $D3$. The terminal electrode 4 includes an electrode portion $4a$ and an electrode portion $4b$. The electrode portion $4a$ and the electrode portion $4b$ are connected at the ridge portion (the corner portion formed by the main face $2c$ and the end face $2b$) of the element body 2 , and are electrically connected to each other. In the present embodiment, the electrode portion $4a$ and the electrode portion $4b$ are integrally provided and are continuous with each other. The electrode portion $4a$ is provided on the end face $2b$ and extends along the first direction $D1$. The electrode portion $4a$ has a rectangular shape when viewed from the second direction $D2$. The electrode portion $4b$ is provided on the main face $2c$ and extends along the second direction $D2$. The electrode portion $4b$ has a rectangular shape when viewed from the first direction $D1$.

The terminal electrodes 3 and 4 each are formed by, for example, laminating a plurality of electrode layers. The electrode layers each are provided in a defective portion formed in the corresponding insulator layer. The defective portions form the recesses in which the terminal electrodes 3 and 4 are disposed. The electrode layers are formed by firing a conductive paste. The conductive paste contains a metal component and a glass component. The metal component is contained in a conductive material and is, for example, Ag or Pd. The glass component is a compound of the elements constituting the element body 2 and is the same component as the glass component contained in the element body 2 . The content of the glass component is only required to be appropriately set. In the actual terminal electrodes 3 and 4 , the electrode layers are integrated in such a way that boundaries between the electrode layers cannot be visually recognized.

The coil 10 and the connecting conductors 23 and 24 are disposed in the element body 2 and are not exposed from the element body 2 . The coil 10 has a pair of end portions $10a$. A first end portion $10a$ is electrically connected to the terminal electrode 4 by the connecting conductor 23 . A second end portion $10a$ is electrically connected to the terminal electrode 3 by the connecting conductor 24 . The coil 10 includes a coil axis AX along the first direction $D1$.

The coil 10 includes a plurality of coil conductors 11 , 12 , and 13 and through-hole conductors 21 and 22 (see FIG. 3). In the present embodiment, the coil 10 includes a first coil conductor 11 , a second coil conductor 12 , and a third coil conductor 13 . The first coil conductor 11 , the second coil conductor 12 , and the third coil conductor 13 are disposed to be separated from each other in the first direction $D1$. The coil conductors 11 , 12 , and 13 are disposed in the order of the first coil conductor 11 , the second coil conductor 12 , and the third coil conductor 13 along the first direction $D1$.

The first coil conductor 11 is disposed closest to the main face $2c$ and is opposed to the main face $2c$ in the first direction $D1$. The first coil conductor 11 is opposed to the electrode portions $3b$ and $4b$ in the first direction $D1$. The third coil conductor 13 is disposed closest to the main face $2d$ and is opposed to the main face $2d$ in the first direction $D1$. The second coil conductor 12 is disposed between the first coil conductor 11 and the third coil conductor 13 in the first direction $D1$. The second coil conductor 12 and the third

coil conductor 13 are disposed closer to the main face $2d$ than the first coil conductor 11 .

The first coil conductor 11 , the second coil conductor 12 , and the third coil conductor 13 each have a shape in which a part of the loop is disconnected, and each have a first end portion and a second end portion. The first coil conductor 11 , the second coil conductor 12 , and the third coil conductor 13 are electrically connected to each other.

The first end portion of the first coil conductor 11 is connected to the electrode portion $4a$ via the connecting conductor 23 . The first end portion of the first coil conductor 11 constitutes the first end portion $10a$ of the coil 10 . The connecting conductor 23 extends along the second direction $D2$ and connects the first end portion of the first coil conductor 11 and the electrode portion $4a$. In the present embodiment, the first coil conductor 11 and the connecting conductor 23 are integrally formed.

The second end portion of the first coil conductor 11 is connected to the first end portion of the second coil conductor 12 via the through-hole conductor 21 . The through-hole conductor 21 extends along the first direction $D1$ and connects the second end portion of the first coil conductor 11 and the first end portion of the second coil conductor 12 . When viewed from the first direction $D1$, the second end portion of the first coil conductor 11 and the first end portion of the second coil conductor 12 overlap each other.

The second end portion of the second coil conductor 12 is connected to the first end portion of the third coil conductor 13 via the through-hole conductor 22 . The through-hole conductor 22 extends along the first direction $D1$ and connects the second end portion of the second coil conductor 12 and the first end portion of the third coil conductor 13 . When viewed from the first direction $D1$, the second end portion of the second coil conductor 12 and the first end portion of the third coil conductor 13 overlap each other.

The second end portion of the third coil conductor 13 is connected to the electrode portion $3a$ via the connecting conductor 24 . The second end portion of the third coil conductor 13 constitutes the second end portion $10a$ of the coil 10 . The connecting conductor 24 extends along the second direction $D2$ and connects the second end portion of the third coil conductor 13 and the electrode portion $3a$. In the present embodiment, the third coil conductor 13 and the connecting conductor 24 are integrally formed.

The coil 10 has a rectangular annular shape when viewed from the first direction $D1$. The coil 10 includes a pair of first coil regions $R1$ and a pair of second coil regions $R2$. The two first coil regions $R1$ are opposed to each other sandwiching the coil axis AX in the second direction $D2$. The two second coil regions $R2$ are opposed to each other sandwiching the coil axis AX in the third direction $D3$.

In the present embodiment, in the first coil region $R1$ on the end face $2a$ side (close to the end face $2a$), the first coil conductor 11 and the second coil conductor 12 are disposed, extend along the third direction $D3$, and are opposed to the end face $2a$ and the electrode portion $3a$. In the first coil region $R1$ on the end face $2b$ side (close to the end face $2b$), the first coil conductor 11 , the second coil conductor 12 , and the third coil conductor 13 are disposed, extend along the third direction $D3$, and are opposed to the end face $2b$ and the electrode portion $4a$.

In the second coil region $R2$ on the side face $2e$ side (close to the side face $2e$), the first coil conductor 11 , the second coil conductor 12 , and the third coil conductor 13 are disposed, extend along the second direction $D2$, and are opposed to the side face $2e$. In the second coil region $R2$ on the side face $2f$ side (close to the side face $2f$), the first coil

conductor **11** and the second coil conductor **12** are disposed, extend along the second direction **D2**, and are opposed to the side face **2f**.

As shown in FIGS. 4 and 5, the width **W1** of the first coil conductor **11** is narrower than the width **W2** of the second coil conductor **12** and the width **W3** of the third coil conductor **13**. In the present embodiment, the width **W2** is narrower than the width **W3**. That is, the widths **W1**, **W2**, and **W3** of the coil conductors **11**, **12**, and **13** become narrower toward the main face **2c**. In other words, a coil conductor disposed closer to the main face **2c** has a narrower width. Here, the widths **W1**, **W2**, and **W3** in the first coil region **R1** are the lengths of the coil conductors **11**, **12**, and **13** in the second direction **D2**. The widths **W1**, **W2**, and **W3** in the second coil region **R2** are the lengths of the coil conductors **11**, **12**, and **13** in the third direction **D3**.

In the present embodiment, the heights **T1**, **T2**, and **T3** of the coil conductors **11**, **12**, and **13** are equal to each other. The heights **T1**, **T2**, and **T3** are the lengths of the coil conductors **11**, **12**, and **13** in the first direction **D1**. Since the heights **T1**, **T2**, and **T3** are equal to each other, it is possible to prevent the height of the multilayer coil component **1** (the length in the first direction **D1**) from increasing and to lower the size as compared with the height **T1** being higher than the heights **T2** and **T3**. If the height of the multilayer coil component **1** has been set, it is possible to prevent the number of turns of the coil **10** from decreasing. Accordingly, the inductance (**L**) of the multilayer coil component **1** is maintained.

The aspect ratio **T1/W1** of the first coil conductor **11** is higher than the aspect ratio **T2/W2** of the second coil conductor **12** and the aspect ratio **T3/W3** of the third coil conductor **13**. In the present embodiment, the aspect ratio **T2/W2** is higher than the aspect ratio **T3/W3**. That is, the aspect ratios **T1/W1**, **T2/W2**, and **T3/W3** of the coil conductors **11**, **12**, and **13** become higher toward the main face **2c**. In other words, a coil conductor disposed closer to the main face **2c** has a higher aspect ratio.

In the present embodiment, the cross-sectional area of the first coil conductor **11** is smaller than the cross-sectional area of the second coil conductor **12** and the cross-sectional area of the third coil conductor **13**. The cross-sectional area of the second coil conductor **12** is smaller than the cross-sectional area of the third coil conductor **13**. That is, the cross-sectional areas of the coil conductors **11**, **12**, and **13** become smaller toward the main face **2c**. In other words, a coil conductor disposed closer to the main face **2c** has a smaller cross-sectional area. Here, the cross-sectional areas of the coil conductors **11**, **12**, and **13** are the areas of the cross-section orthogonal to the axial direction of the coil conductors **11**, **12**, and **13**.

The width **W1** and the height **T1** are constant throughout the first coil conductor **11**. The width **W2** and the height **T2** are constant throughout the second coil conductor **12**. The width **W3** and the height **T3** are constant throughout the third coil conductor **13**.

As shown in FIG. 4, in the second coil region **R2** on the side face **2e** side, an outer edge **11a** of the first coil conductor **11** aligns with an outer edge **12a** of the second coil conductor **12** and an outer edge **13a** of the third coil conductor **13** when viewed from the first direction **D1**. An inner edge **11b** of the first coil conductor **11** is positioned closer to the outer side (side face **2e**) than an inner edge **12b** of the second coil conductor **12** and an inner edge **13b** of the third coil conductor **13**. The inner edge **12b** is positioned closer to the outer side than the inner edge **13b** when viewed from the first direction **D1**. That is, the inner edges **11b**, **12b**, and **13b**

of the coil conductors **11**, **12**, and **13** become positioned closer to the outer side toward the main face **2c**. In other words, a coil conductor disposed closer to the main face **2c** has an inner edge positioned closer to the outer side. In the second coil region **R2** on the side face **2f** side, the outer edge **11a** aligns with the outer edge **12a** when viewed from the first direction **D1**. The inner edge **11b** is positioned closer to the outer side (side face **2f**) than the inner edge **12b**.

As shown in FIG. 5, in the first coil region **R1** on the end face **2b** side, the inner edge **11b** aligns with the inner edge **12b** and the inner edge **13b** when viewed from the first direction **D1**. The outer edge **11a** is positioned closer to the inner side (end face **2a**) than the outer edge **12a** and the outer edge **13a**. When viewed from the first direction **D1**, the outer edge **12a** is positioned closer to the inner side than the outer edge **13a**. That is, the outer edges **11a**, **12a**, and **13a** of the coil conductors **11**, **12**, and **13** become positioned closer to the inner side toward the main face **2c**. In other words, a coil conductor disposed closer to the main face **2c** has an outer edge positioned closer to the inner side. In the first coil region **R1** on the end face **2a** side, the inner edge **11b** aligns with the inner edge **12b** when viewed from the first direction **D1**. The outer edge **11a** is positioned closer to the inner side (the end face **2b**) than the outer edge **12a**.

The first coil conductor **11**, the second coil conductor **12**, the third coil conductor **13**, and the connecting conductors **23** and **24** each contain a conductive material. The conductive material contains Ag or Pd. The first coil conductor **11**, the second coil conductor **12**, the third coil conductor **13**, and the connecting conductors **23** and **24** each are formed as a sintered body of a conductive paste containing a conductive material powder. The conductive material powder contains, for example, Ag powder or Pd powder.

In the present embodiment, the first coil conductor **11**, the second coil conductor **12**, the third coil conductor **13**, and the connecting conductors **23** and **24** contain the same conductive material as the terminal electrodes **3** and **4**. The first coil conductor **11**, the second coil conductor **12**, the third coil conductor **13**, and the connecting conductors **23** and **24** may contain a conductive material different from the terminal electrodes **3** and **4**.

The first coil conductor **11**, the second coil conductor **12**, the third coil conductor **13**, and the connecting conductors **23** and **24** each are provided in a defective portion formed in the corresponding insulator layer. The first coil conductor **11**, the second coil conductor **12**, the third coil conductor **13**, and the connecting conductors **23** and **24** each are formed by firing the conductive paste positioned in the defective portion formed in a green sheet.

The defective portion formed in the green sheet is formed by, for example, the following process. First, a green sheet is formed by applying an element-body paste containing a constituent material of the insulator layer and a photosensitive material on a substrate. The substrate is, for example, a PET film. The photosensitive material contained in the element-body paste may be either a negative type or a positive type, and a known photosensitive material can be used. Then, using the mask corresponding to the defective portion, the green sheet is exposed and developed by a photolithography method to form the defective portion in the green sheet on the substrate. The green sheet in which the defective portion is formed is an element-body pattern.

The electrode layers, the first coil conductor **11**, the second coil conductor **12**, the third coil conductor **13**, and the connecting conductors **23** and **24** are formed by, for example, the following process.

First, a conductor material layer is formed by applying a conductive paste containing a photosensitive material on a substrate. The photosensitive material contained in the conductive paste may be either a negative type or a positive type, and a known photosensitive material can be used. Then, using the mask corresponding to the defective portion, the conductor material layer is exposed and developed by a photolithography method to form a conductor pattern corresponding to the shape of the defective portion on the substrate.

The multilayer coil component **1** is obtained by, for example, the following process following the process described above. The conductor pattern is combined with the defective portion of the element-body pattern to prepare a sheet in which the element-body pattern and the conductor pattern are in the same layer. After heat-treating the laminate obtained by laminating the predetermined number of prepared sheets, a plurality of green chips are obtained from the laminate. In this process, the green laminate is cut into chips by, for example, a cutting machine. Accordingly, a plurality of green chips having a predetermined size can be obtained. Next, the green chips are fired. With this firing, the multilayer coil component **1** is obtained. The surface of each of the terminal electrodes **3** and **4** may be formed with a plating layer. The plating layer is formed by, for example, electroplating or electroless plating. The plating layer contains, for example, Ni, Sn, or Au.

Second Embodiment

With reference to FIGS. 6 to 10, a multilayer coil component **1A** according to a second embodiment will be described focusing on the differences from the multilayer coil component **1** (see FIGS. 1 to 5). In FIGS. 6 to 8, an element body **2** is shown by a broken line. In the multilayer coil component **1A**, a terminal electrode **3** does not include an electrode portion **3a** and includes only an electrode portion **3b**, and a terminal electrode **4** does not include an electrode portion **4a** and includes only an electrode portion **4b**. The multilayer coil component **1A** includes connecting conductors **25** and **26** instead of the connecting conductors **23** and **24** of the multilayer coil component **1**. The connecting conductors **25** and **26** each have, for example, a columnar shape with a circular cross section and extend along the first direction **D1**. The connecting conductor **25** electrically connects the terminal electrode **4** and a first end portion **10a** of a coil **10**. The connecting conductor **26** electrically connects the terminal electrode **3** and a second end portion **10a** of the coil **10**.

A first coil conductor **11** and a second coil conductor **12** each are formed with a recess at a position overlapping the second end portion of **10a** of the coil **10** when viewed from the first direction **D1**. The recess is provided to avoid interference with the connecting conductor **26**. The inner surfaces of the recesses are opposed to the outer surface of the connecting conductor **26**. The connecting conductor **26** is disposed separated from the first coil conductor **11** and the second coil conductor **12** due to the recesses.

As shown in FIG. 9, in a second coil region **R2** on a side face **2e** side, an outer edge **11a** aligns with an outer edge **12a** and an outer edge **13a** when viewed from the first direction **D1**. An inner edge **11b** is positioned closer to the outer side (side face **2e**) than an inner edge **12b** and an inner edge **13b**. The inner edge **12b** is positioned closer to the outer side than the inner edge **13b** when viewed from the first direction **D1**. That is, the inner edges **11b**, **12b**, and **13b** of the coil conductors **11**, **12**, and **13** become positioned closer to the outer side (side face **2e**) than the inner edge **12b**.

outer side toward the main face **2c**. In other words, a coil conductor disposed closer to the main face **2c** has an inner edge positioned closer to the outer side. In the second coil region **R2** on the side face **2f** side, the outer edge **11a** aligns with the outer edge **12a** when viewed from the first direction **D1**. The inner edge **11b** is positioned closer to the outer side (side face **2f**) than the inner edge **12b**.

As shown in FIG. 10, in a first coil region **R1** on an end face **2b** side, the outer edge **11a** aligns with the outer edge **12a** and the outer edge **13a** when viewed from the first direction **D1**. The inner edge **11b** is positioned closer to the outer side (the end face **2b**) than the inner edge **12b** and the inner edge **13b**. The inner edge **12b** is positioned closer to the outer side than the inner edge **13b** when viewed from the first direction **D1**. That is, the inner edges **11b**, **12b**, and **13b** of the coil conductors **11**, **12**, and **13** become positioned closer to the outer side toward the main face **2c**. In other words, a coil conductor disposed closer to the main face **2c** has an inner edge positioned closer to the outer side. In the first coil region **R1** on the end face **2a** side, the outer edge **11a** aligns with the outer edge **12a** when viewed from the first direction **D1**. The inner edge **11b** is positioned closer to the outer side (the end face **2a**) than the inner edge **12b**.

As described above, in each of the multilayer coil components **1** and **1A**, the first coil conductor **11** of the coil conductors **11**, **12**, and **13** is disposed closest to the main face **2c** and is opposed to the electrode portions **3b** and **4b**. Thus, stray capacitance is formed between the first coil conductor **11** and the electrode portions **3b** and **4b** depending on the area where the first coil conductor **11** is opposed to the electrode portions **3b** and **4b**. The width **W1** of the first coil conductor **11** is narrower than the width **W2** of the second coil conductor **12** disposed closer to the main face **2d** than the first coil conductor **11**. Thus, the area where the first coil conductor **11** is opposed to the electrode portions **3b** and **4b** is smaller than that when the width **W1** is about equal to the width **W2**. For this reason, it is possible to reduce the stray capacitance formed between the first coil conductor **11** and the electrode portions **3b** and **4b**. Accordingly, it is possible to prevent the self-resonant frequency of the multilayer coil components **1** and **1A** from lowering.

The aspect ratio **T1/W1** of the first coil conductor **11** is higher than the aspect ratio **T2/W2** of the second coil conductor **12**. Thus, it is possible to increase the cross-sectional area of the first coil conductor **11** as compared with the aspect ratio **T1/W1** being about equal to the aspect ratio **T2/W2**. Accordingly, it is possible to prevent the Q-values of the multilayer coil components **1** and **1A** from decreasing. From the above, it is possible to prevent deterioration in the characteristics of the multilayer coil components **1** and **1A**.

The widths **W1**, **W2**, and **W3** of the coil conductors **11**, **12**, and **13** become narrower toward the main face **2c**. The aspect ratios **T1/W1**, **T2/W2**, and **T3/W3** of the coil conductors **11**, **12**, and **13** become higher toward the main face **2c**. Thus, it is possible to further prevent the deterioration in the characteristics of the multilayer coil components **1** and **1A**.

In each of the multilayer coil components **1** and **1A**, the outer edge **11a** aligns with the outer edge **12a** in the second coil regions **R2** when viewed from the first direction **D1**. The width **W1** is narrower than the width **W2**. Thus, the inner edge **11b** is positioned closer to the outer side than the inner edge **12b** when viewed from the first direction **D1**. Thus, the inner diameter of the first coil conductor **11** is larger than that when the inner edge **11b** aligns with the inner edge **12b** when viewed from the first direction **D1**. Therefore, it is possible to improve the Q value and the inductance (L).

11

In the multilayer coil component 1A, the outer edge 11a aligns with the outer edge 12a when viewed from the first direction D1 not only in the second coil regions R2 but also in the first coil regions R1. Thus, it is possible to further improve the Q value and the inductance (L).

In the multilayer coil component 1, the first coil conductor 11 is opposed to the electrode portions 3b and 4b in the first coil regions R1. The inner edge 11b aligns with the inner edge 12b in the first coil regions R1 when viewed from the first direction D1. Thus, the distance between the first coil conductor 11 and the electrode portions 3b and 4b is widened. Thus, it is possible to reduce the stray capacitance formed between the first coil conductor 11 and the electrode portions 3b and 4b. Accordingly, it is possible further prevent the self-resonant frequency of the multilayer coil component 1 from lowering while improving the Q value and the inductance (L).

The embodiments of the present invention have been described above; the present invention is not necessarily limited to the above described embodiments, and can be variously changed without departing from the gist.

The cross-sectional area of the first coil conductor 11 may be equal to the cross-sectional area of the second coil conductor 12, as shown in FIG. 11. In this case, it is possible to reliably prevent the Q value from decreasing. In addition, the cross-sectional area of the first coil conductor 11 may be equal to the cross-sectional area of the second coil conductor 12 and the cross-sectional area of the third coil conductor 13. In this case, it is possible to more reliably prevent the Q value from decreasing.

In the above embodiments, the coil 10 having the first coil conductor 11, the second coil conductor 12, and the third coil conductor 13 has been exemplified. However, the number of coil conductors forming the coil 10 is not limited to the above.

What is claimed is:

1. A multilayer coil component comprising:
an element body having a rectangular parallelepiped shape and including a first main face and a second main face opposed to each other in a first direction, a first end face and a second end face opposed to each other in a second direction intersecting the first direction, and a first side face and a second side face opposed to each other in a third direction intersecting the first direction and the second direction;
a coil including a coil axis along the first direction and disposed in the element body; and
a terminal electrode electrically connected to the coil,
wherein
the terminal electrode includes a main-face electrode portion provided on the first main face,
the coil includes a plurality of coil conductors disposed to be separated from each other in the first direction and electrically connected to each other,
the plurality of coil conductors includes a first coil conductor disposed closest to the first main face to oppose to the main-face electrode portion and a second coil conductor disposed closer to the second main face than the first coil conductor,
the first coil conductor has a width narrower than a width of the second coil conductor,
the first coil conductor has an aspect ratio higher than an aspect ratio of the second coil conductor,
the first coil conductor has, when viewed from the first direction, (i) an outer edge aligning with an outer edge of the second coil conductor and an inner edge not aligning with an inner edge of the second coil con-

12

tor, or (ii) an outer edge not aligning with an outer edge of the second coil conductor and an inner edge aligning with an inner edge of the second coil conductor, and the first coil conductor has a cross-sectional area equal to a cross-sectional area of the second coil conductor.

5 2. The multilayer coil component according to claim 1, wherein

the plurality of coil conductors has a width becoming narrower toward the first main face, and
10 the plurality of coil conductors has an aspect ratio becoming higher toward the first main face.

15 3. The multilayer coil component according to claim 1, wherein

the first coil conductor has, when viewed from the first direction, an outer edge aligning with an outer edge of the second coil conductor.

15 4. The multilayer coil component according to claim 1, wherein

the terminal electrode further includes an end-face electrode portion provided on the first end face, the first coil conductor is opposed to the end-face electrode portion,

20 the coil includes a pair of first coil regions opposed to each other sandwiching the coil axis in the second direction, and

25 the inner edge of the first coil conductor has a first portion aligning with a first portion of the inner edge of the second coil conductor in the pair of first coil regions.

30 5. The multilayer coil component according to claim 4, wherein

the coil includes:

35 a pair of second coil regions opposed to each other sandwiching the coil axis in the third direction, and the inner edge of the first coil conductor has a second portion that aligns with a second portion of the inner edge of the second coil conductor in the pair of second coil regions.

6. A multilayer coil component comprising:

an element body having a rectangular parallelepiped shape and including a first main face and a second main face opposed to each other in a first direction, a first end face and a second end face opposed to each other in a second direction intersecting the first direction, and a first side face and a second side face opposed to each other in a third direction intersecting the first direction and the second direction;

40 a coil including a coil axis along the first direction and disposed in the element body; and

a terminal electrode electrically connected to the coil,
wherein

the terminal electrode includes a main-face electrode portion provided on the first main face,

the coil includes a plurality of coil conductors disposed to be separated from each other in the first direction and electrically connected to each other,

the plurality of coil conductors includes a first coil conductor disposed closest to the first main face to oppose to the main-face electrode portion and a second coil conductor disposed closer to the second main face than the first coil conductor,

the first coil conductor has a width narrower than a width of the second coil conductor,

the first coil conductor has an aspect ratio higher than an aspect ratio of the second coil conductor,

60 a length of each of the plurality of coil conductors in the first direction is longer than a distance between adjacent coil conductors in the first direction, and

13

the first coil conductor has a cross-sectional area equal to a cross-sectional area of the second coil conductor.

7. The multilayer coil component according to claim 6, wherein

the plurality of coil conductors has a width becoming 5 narrower toward the first main face, and

the plurality of coil conductors has an aspect ratio becoming higher toward the first main face.

8. The multilayer coil component according to claim 6, wherein

the first coil conductor has, when viewed from the first direction, an outer edge aligning with an outer edge of the second coil conductor.

9. The multilayer coil component according to claim 6, wherein

the terminal electrode further includes an end-face electrode portion provided on the first end face, 15

the first coil conductor is opposed to the end-face electrode portion,

14

the coil includes a pair of first coil regions opposed to each other sandwiching the coil axis in the second direction, and

the first coil conductor has, when viewed from the first direction, an inner edge with a first portion aligning with a first portion of an inner edge of the second coil conductor in the pair of first coil regions.

10. The multilayer coil component according to claim 9, wherein

the coil includes:

a pair of second coil regions opposed to each other sandwiching the coil axis in the third direction, and

when viewed from the first direction, the inner edge of the first coil conductor has a second portion that aligns with a second portion of the inner edge of the second coil conductor in the pair of second coil regions.
